ATTORNEY

UNITED STATES PATENT OFFICE.

PAUL G. BLANCHET, OF SOUTH ORANGE, NEW JERSEY.

CARD CASE.

Application filed May 26, 1921. Serial No. 472,639.

To all whom it may concern:

Be it known that I, PAUL G. BLANCHET, a citizen of the United States, residing at South Orange, in the county of Essex and

5 State of New Jersey, have invented a certain new and useful Improvement in Card-cases, of which the following is a specification.

The invention relates to cardcases of the 10 envelope type, and the object of the invention is to provide a simple, easily manufactured and inexpensive case, adapted to be formed of paper, containing a card-pocket and a conveniently arranged and presented 15 dated memorandum pad.

The invention consists in certain novel features of construction and arrangement by which the above objects are attained, to be hereinafter described and claimed.

20 The accompanying drawings form a part of this specification and show an approved form of the invention.

Figure 1 is a face view of the card case with the wallet-flap closed.

25 Figure 2 is a similar view with the wallet-flap open to expose the memorandum pad and pocket.

Figure 3 is a perspective view showing the case in the partly opened condition.

30 Figure 4 is a transverse section on the line IV—IV in Figure 1.

Figure 5 is a longitudinal section taken on the line V—V in Figure 1 and on a greatly enlarged scale.

35 Figures 6, 7 and 8 are face views of three successive leaves of the pad, showing the system of dating such leaves.

Figure 9 is a face view of the blank which when folded forms the case.

40 Similar reference numerals indicate the same parts in all the figures.

Referring to the drawings, 1 is the face or back of the envelope-like case, 2 is the pocket-flap folded thereon and forming 45 therewith the pocket 3, held and closed at one end by the side-flap 4 pasted upon the outer end margin of the pocket-flap.

The memorandum pad 5, to be described, lies upon the outer face of the pocket-flap 2 50 and may be pasted or otherwise secured thereto; it is held in position and its cemented edge covered by the side-flap 6 overlapped and pasted upon such cemented margin.

55 The side-flap 6 thus folded and pasted closes the other end of the pocket 3. The

wallet-flap 7 of practically the same dimensions as the back 1 is arranged to fold upon the pad and close the open mouth of the pocket.

The back 1, side-flaps 4 and 6, pocket-flap 2 and wallet-flap 7 are preferably in a single sheet of strong paper, as shown in Figure 9, cut from the stock by dies or otherwise in the manner employed in envelope manu- 60 65

The memorandum pad 5 is formed of superposed leaves cemented as usual, or otherwise joined, at one end only, each having a line of perforations 8 immediately adjacent 70 the overlapped edge of the side-flap 6, and a second line of perforations 9 dividing the free portion of the leaf into two approximately equal sections, the lower section 10 adapted to be first torn away along the line 75 9, and the upper section 11 of the same leaf to be next removed by tearing along the line 8.

The sections of the leaves are intended to bear the days of the week and their corresponding dates, with space for writing short memoranda, and the pad is preferably arranged to include a single month only, the entire case to be discarded at the end of such month and replaced by another containing 85 a pad for the succeeding month.

Each memorandum leaf is for two succeeding days, the lower section 10 of the first leaf bearing the earlier date, as shown by the three succeeding leaves illustrated in 90 Figures 6, 7 and 8, in which "Wednesday, June 1" appears on the lower section of Figure 6, and "Thursday, June 2" appears on the upper section, followed by "Friday, June 3" on the lower section of the next leaf, 95 see Figure 7, with "Saturday, June 4" on its upper section. Thus arranged the memorandum pad always shows two successive dates. When the lower section of the first leaf is removed the upper section bearing 100 "Thursday, June 2" remains while the lower section of the second leaf, exposed by such removal, bears "Friday, June 3" and when the upper section of the first leaf is torn off, the entire second leaf with its dates is exposed, and so on through the entire pad.

The outer face of the sheet forming the case may be printed to imitate leather or otherwise ornamented to produce a pleasing appearance.

110 Cards, railway tickets, or the like, carried in the pocket 3 tend to stiffen the case, aided

21 by the stiffness afforded by the leaves of
the pad 5.

Although the pad is shown as having its leaves divided into two sections, it will be understood that the leaves may be divided into three or more having dates arranged according to the above described system.

I claim:—

1. The cardcase described, comprising a back, side-flaps, pocket-flap and wallet-flap in a single sheet, said pocket-flap adapted to fold upon said back, a memorandum pad lying upon the exposed face of said folded pocket-flap, one of said side-flaps folded upon and pasted to said pocket-flap to form one closed end of a pocket, the other side-flap folded upon and pasted to said pad to hold the latter and form the other closed end of such pocket, and said wallet-flap adapted to fold upon and cover said pad and pocket.

2. In a cardcase having a wallet-flap, a dated memorandum pad covered by such flap and consisting of superposed leaves secured together at their upper margins and each leaf divided into sections by weakened lines, the lowermost section bearing the earliest date and the succeeding section bearing the next succeeding date, and the lowermost sec-

tion of the next leaf bearing the date next succeeding the date borne by the uppermost section of the preceding leaf.

3. The cardcase described, comprising a back, side-flaps, pocket-flap and wallet-flap in a single sheet, said pocket-flap adapted to fold upon said back, a memorandum pad lying upon the exposed face of said folded pocket-flap, one of said side-flaps folded upon and pasted to said pocket-flap to form one closed end of a pocket, the other side-flap folded upon and pasted to said pad to hold the latter and form the other closed end of such pocket, and said wallet-flap adapted to fold upon and cover said pad and pocket, said pad comprising superposed dated leaves secured together at their upper margins and each leaf divided into sections by weakened lines, the lowermost section bearing the earliest date and the succeeding section bearing the next succeeding date, and the lowermost section of the next leaf bearing the date next succeeding the date borne by the uppermost section of the preceding leaf.

In testimony that I claim the invention above set forth I affix my signature.

PAUL G. BLANCHET.
